FIVE AND TEN DRUM FLUSH UNIT

Robert Lee Kaye, Newark, N. J.

Application December 14, 1950, Serial No. 200,884

4 Claims. (Cl. 134—107)

1

The present invention concerns the reconditioning of metal barrels and drums by knife spraying to remove internal deposits of all sorts, flushing and rinsing so as to obtain a clean surface ready for painting or to receive new contents without contamination.

It is the object of the invention to provide a novel flush and rinse unit having revolving knife spray nozzles which cover the entire inside of a drum.

It is an object of the invention to provide variable time control means whereby a drum is put through a flush, rinse and drain cycle repetitively.

It is an object of the invention to provide proper balance between volume and pressure of fluid during the cleaning operation.

In the cleaning and reconditioning of drums one of the high cost operations is chaining or the removal of resistant coatings or contents by revolving the drum with steel balls or a length of chain inside. In some stubborn cases sand blasting is employed. Because of the greatly increased cost of cleaning such "chainers" are avoided and bring a much lower price on the market. Tests have shown that the present invention reduces the number of drums which require chaining by as much as 50% or more.

In the cleaning of drums with prior art equipment one serious problem has been the collection of cleaning fluid within the drum in such quantities as to impede and greatly reduce the efficiency of the cleaning action. This condition almost necessarily follows from the rate of input of fluid into the barrel and the relatively small effective bung area for drainage during the cleaning operation. With the present invention a drum to be cleaned is positioned horizontally with its bung down. A rotating fan spray nozzle extends into the drum. Optimum operating conditions have been found to be a feed of twenty gallons per minute at eighty pounds pressure. This flow causes about two inches of fluid to collect in the bottom or bung side of the drum during cleaning. At this level sufficient pressure builds up within the drum to stabilize conditions by forcing a fluid flow out of the bung of twenty gallons per minute.

The fluid layer, which in previous methods and equipment for cleaning reached greater depths, has previously made any spray cleaning ineffective on the lower portion of the drum.

It is an object of the invention to provide a cleaning fluid spray which will effectively cut through a water cushion and clean at the bottom thereof.

2

It is an object of the invention to provide a flushing and rinsing unit for drums comprising a tank having rotating fan shaped spray nozzle therein arranged to project inside of drums to be cleaned, heating means for a hot caustic solution, straining means for said solution and pressure circulation to maintain the fan shaped spray.

In the drawing like numbers refer to like parts throughout.

Fig. 1 is a plan view of one form the invention may take.

Fig. 2 is a side elevation partly sectioned view of Fig. 1.

Fig. 3 is a sectional view along the nozzle axis.

Fig. 4 is a fragmentary view of a detail of construction.

Fig. 5 is a detail of the nozzle drive mechanism.

One form of flush and rinse unit comprises an elongate rectangular tank 10 preferably of metal such as quarter inch steel plate or the like having inner bracing angle members 11 positioned about six inches below the upper elongate edge of tank 10. Angle members 11 afford a flange like surface or shelf 12 along each side of tank 10 and are braced by cross angles 13. The upper elongate edges of tank 10 are provided with depressions 14 forming pairs of drum support circular segments having a radius substantially the same as that of a drum to be cleaned so as to act as an effective holding means to anchor the drum while cleaning. Depressions 14 are shallow so that it is possible to roll drums in and out of them by hand. Where heavier drums are to be cleaned it may be well to make the segmental radius larger so that the drums can be rolled out more easily.

Cross angles 13 are preferably located at each pair of depressions 14 and provide support for bearings 15 in which is journaled elongate drive shaft 16 extending the length of tank 10 and at one end thereof to a gear reducer 17 and one horse power drive motor 18 mounted on a shelf or platform 19 on the outside of an end wall of tank 10. Shaft 16 has a worm 20 keyed thereto adjacent each bearing 15. Near the middle of tank 10 and paralleling shaft 16 is mounted a cleaning fluid supply header 21 capable of withstanding a hot caustic cleaning fluid at an operating pressure of over eighty pounds per square inch. Header 21 projects through an end wall of tank 10 and is arranged to be coupled with a caustic fluid supply or a circulating pump 22.

55 Upright feed pipes 23 are connected to header

21 opposite the nadir of depressions 14. A rotating head portion 24 is mounted on each feed pipe 23 by means of a bearing assembly having a packing gland or the like. A pinion 25 is keyed to rotating head portion 24 and mates with worm 20. Head portion 24 is provided with a nozzle 26 producing a fan shaped spray.

Nozzle 26 may be constructed by closing one end of a pipe elbow 27 and saw cutting a $\frac{1}{16}$ inch slot 28 closely adjacent the closed end. Where the closing disk 29 of elbow 27 is held by one or more connections 30, which obstruct fluid flow, connection 30 is at one side not at the top or bottom. Where two connections 30 are employed they should not be on either the vertical or horizontal axis. In this way dead spots of fan action are avoided as all interior parts of the drum receive sprayed cleaning solution directly at least once every revolution of nozzle 26. Slot 28 should not cover less than 120 degrees of arc.

Heating coils 31 for steam or the like are provided at one side of tank 10. A drain 32 is located at the bottom of tank 10 and is closed by removable overflow pipe 33 having a bail or handle 34. A removable cover of number four expanded metal grating 35 lies loosely on the surfaces 12 and covers the top of tank 10. Cover 35 is provided with a series of apertures through which rotating head portions 24 project with ample clearance to permit cleaning fluid to flow back into tank 10 from the drums being cleaned. Cover 35 is well below the lowest point of depressions 14 and nozzles 26 project well above the edge of tank 10 so as to enter a drum and be completely enclosed thereby.

By deepening depressions 14 nozzles 26 may be lowered below the edge of the walls of tank 10. This construction guards the nozzles 26 and materially speeds up handling if combined with the movable rails 48 of Fig. 4. A pair of these rails 48 runs the entire length of tank 10 and may be quickly raised to provide a smooth running surface for positioning or removing drums. Deep depressions 39 make this construction desirable so that the drums may be handled more easily. Rails 48 are held by bolts 40 which ride in slots 41 in the upper part of the walls of tank 10. Rails 48 may be raised and lowered by cams 42 and levers 43 adjacent each end of the rails 48. Each pair of cams 42 at one end are preferably joined by a rod 44 running across tank 10 and the pair is operated by a single lever 43.

While an external supply of caustic solution may be fed to main 21, it is preferred to utilize tank 10 as a reservoir in which the fluid supply is heated, screened and recirculated. A ten or fifteen horse power motor 36 drives pump 22. Four removable screens 37 are mounted at an angle of forty-five degrees in the end of tank 10 adjacent intake 38 of pump 22. Screens 37 are made of 0.099 wire giving a seventy-five percent opening. Tilting provides a screening area of twelve square feet and prevents rapid clogging.

In the form of invention shown in Figs. 1 and 2, rinse action is obtained by supplying steam to the drums through header 21 and nozzles 26.

An automatic variable timer as shown in my copending application for double end chime resealer of even date herewith having a selector switch for repeating a spray cycle from one to ten times may be used to control the present invention. Best results are obtained by pumping for twenty seconds and stopping the flow for ten seconds so the drums can drain. A variable dial setting permits adjustment of the pumping and

drain cycle from zero to fifty-five seconds. After the final drain another timer operates a magnetic steam valve to give a rinse of steam through nozzles 26 for about twenty seconds. During the flush, drain and steam rinse period a red light is on. When the final rinse is complete a green light comes on to indicate the drums are ready for removal and are to be replaced.

The operation of the device is as follows:

Drums to be cleaned are rolled onto the upper edges of the walls of tank 10 until they rest in depressions 14 with their bungs down and head portion 24 with nozzle 26 extending into the drum. In practice the invention is normally constructed so that the nozzle is nearer the bottom of the horizontal drum than the top both because the fan spray must cut through the two inch solution cushion inside the drum, also the shorter head portion 24 is made the easier and more quickly the nozzle can be inserted through the bung and removed therefrom. Again the lower head portion 24 is made the less likely it will be damaged and bent out of line.

Where a flush and rinse unit is designed for a drum of a given diameter then the height of nozzle 26 above the edge of the walls of tank 10 is such that the drum may be pivoted at the edge of depression 14 and the nozzle 26 enters the drum without lifting. This construction makes removal after cleaning even more simple as the drum is already positioned. The height of nozzle 26 above the edge of tank 10 is preferably of the order of one-third the radius of a drum to be cleaned. Nozzle 26 extends above the bottom of depression about two-thirds the radius of a drum.

With the drums in position and all the nozzles 26 covered hot caustic cleaning fluid is turned into header 24 under a pressure of about eighty pounds per square inch. The cleaning fluid flows into feed pipes 23 through the bearing assembly, head portion 24 and out slot 28 in elbow 27 of nozzle 26. The fluid when discharged under such pressure forms thin fan shaped cutting stream which is sheet like in appearance. The stream can cover 250 or more degrees of arc, the closing disk 29 being held in place by an integral metal connecting link 30 located to one side of the vertical axis as discussed above. This construction is inexpensive and the fan shaped stream may be adjusted by tapping disk 29 with a hammer or prying slot 28 with a screw driver or heavier tool. A flow of about twenty gallons per minute has been selected as optimum for the general purpose machine. One adjusted at $\frac{1}{16}$ slot it is seldom necessary to service this construction which is simple and easily cleaned by unscrewing elbow 27. In special applications disk 29 may be provided with a threaded central post which screws into elbow 27 and by means of which the width of slot 28 may be adjusted over a wide range.

Drive motor 18 is energized and gear reducer 17 rotates shaft 16 in bearings 15. Worm 20 turns pinion 25 causing nozzle 26 to revolve at ten or fifteen revolutions per minute. Slower or faster rates of rotation may be employed depending upon the character of the coating within the drum to be cleaned.

The rotating fan of hot caustic solution has both a knife action and a solvent action and soon removes most coatings. When stable fluid flow conditions are established within a drum being cleaned about two inches of fluid is present in the bottom, but the fan cuts through this as well.

and cleans most effectively. It will be noted that the nozzle 26 is closer to the bottom than the top of the drum and therefore initially has a strong cleaning action before the fluid layer accumulates.

During cleaning fluid runs out of the bungs of the drums, through the openings in expanded metal and into the interior of tank 10 where it is kept hot by coils 31. Hot caustic fluid flows out overflow pipe 33, is strained and recirculated by a pump. Straining may not be necessary if drain 32 is connected to the intake of pump 22 and extra solution is added, as pipe 33 takes fluid only from the top of the tank and solid matter collects in the bottom. This construction would require a two way distributor valve in drain 32, one branch leading to sewage and the other to the intake of pump 22.

After a run of about five minutes, which includes about ten cycles of twenty seconds pumping and ten seconds draining, the fluid flow through header 21 is shut off by a valve and a steam rinse is applied by admitting steam to header 21. The drums are removed by rolling on the edge of tank as soon as the condensed steam has drained out of them.

After a run of about one thousand drums it is usually desirable to lift overflow pipe 33 out of tank 10 by handle 34. All solid matter is washed with the spent cleaning fluid down drain 32 and new caustic solution supplied to tank 10 for the succeeding run. A ten drum unit requires about eight hundred gallons of solution.

While there has been described what is at present considered to be the preferred embodiment of this invention, it will be obvious to those skilled in the art that various changes and modifications may be made therein without departing from the invention, and it is therefore intended in the appended claims to cover in generic terms all such changes and modifications as fall within the true spirit and scope of the invention.

I claim:

1. In combination in a multiple drum cleaning device, an elongate tank, having a plurality of drum positioning means along one long edge thereof, cross frame members corresponding to said drum positioning means and extending across the width of said tank, a header mounted within the tank and extending along its length, a fluid circulating pump connected to supply cleaning fluid under pressure to said header, means to supply fluid from said tank to the intake of said pump, heating means carried by said tank for heating the cleaning fluid in the tank, a drive shaft journaled in bearings carried by

said cross frame members and extending along the length of said tank, a plurality of spaced riser pipes each having a fixed part connected to said header adjacent a cross frame member and a drum positioning means and a rotatable part geared to said drive shaft, each rotatable part having an upstanding nozzle means with a narrow slit therein adjacent its upper end, said slit being arranged to produce a fan shaped knife-like flow of cleaning fluid of high velocity, each said nozzle means being connected to said header through one of said riser pipes having a fixed part and a movable part, drive means connected to said drive shaft and arranged to rotate said shaft at a low controlled speed to maximize the kinetic energy and therefore the knife-like action of said fan-shaped flow of cleaning fluid from said slits by opposing any unbalanced reaction turbine effect of said fluid flow and combination overflow and drain means for said tank comprising an opening in the bottom of said tank and an open ended cylinder removably positioned over said opening whereby overflow fluid will flow over the open end of said cylinder and the removal of the cylinder causes the tank to drain out said opening.

2. The combination set forth in claim 1, filter means within said tank comprising inclined screens closely adjacent that end of said tank from which fluid is withdrawn by said circulating pump.

3. The combination set forth in claim 2, a plurality of spaced anchor means carried by the upper, drum supporting edges of said tank.

4. The combination set forth in claim 3, rail members movably mounted on the side of said tank and movable to a first position in which said anchor means effectively holds drums in cleaning position and movable to a second position in which drums roll free of said anchor means.

ROBERT LEE KAYE.
